UNITED STATES PATENT OFFICE.

ELLIS H. GEMMILL, OF AKRON, OHIO, ASSIGNOR TO THORP & MARTIN TYPEWRITER COMPANY, OF BOSTON, MASSACHUSETTS, A CORPORATION OF MASSACHUSETTS.

CUSHION-TIP FOR THE KEYS OF TYPE-WRITERS AND LIKE MACHINES.

1,189,091.

Specification of Letters Patent. Patented June 27, 1916.

Application filed January 4, 1915. Serial No. 427.

To all whom it may concern:

Be it known that I, ELLIS H. GEMMILL, a citizen of the United States, residing at Akron, in the county of Summit and State 5 of Ohio, have invented certain new and useful Improvements in Cushion-Tips for the Keys of Type-Writers and like Machines, of which the following is a specification.

10 The present invention relates to a cushion cap for the keys of typewriters and like machines, and has for its object to provide a device of this character which will act in an effective manner to absorb any shock incident to the sudden striking of the key by the finger, and which embodies novel features of construction whereby the letter or character of the particular key is applied to the cushion in such a manner that it will 15 neither wear off nor become soiled by continued use.

A further object of the invention is to provide a cushion cap of this character which is comparatively simple and inexpensive in its construction, which can be easily and firmly applied to the key of a typewriter or like machine without the use of any special tools and without the necessity of taking down or altering the keys, 25 which does not render the keys clumsy and awkward to manipulate, and which has the designating character applied thereto in such a manner that it can be readily removed and applied to a new body portion if 30 desired, and will not become soiled or worn by use.

With these and other objects in view, the invention consists in certain novel combinations and arrangements of the parts as will 35 more fully appear as the description proceeds, the novel features thereof being pointed out in the appended claims.

For a full understanding of the invention, reference is to be had to the following description and accompanying drawing, in which:—

Figure 1 is a top plan view of a cushion cap for typewriter keys constructed in accordance with the invention. Fig. 2 is a 40 vertical sectional view through the same. Fig. 3 is a side elevation of the cushion cap showing the same as applied to a typewriter key. Fig. 4 is a vertical sectional view through the cap and the head of the typewriter key to which it is applied. Fig. 5

is a side elevation showing a slight modification in which a different form of retaining ring is employed for securing the hollow resilient cap member to the typewriter key. Fig. 6 is a vertical sectional view through one of the cushion caps, showing a modified construction in which the letter carrying disk is secured to the top of the cap by means of a retaining ring.

Corresponding and like parts are referred to in the following description and indicated in all the views of the drawing by the same reference characters.

One embodiment of the invention is shown by Figs. 1 to 4 of the drawing, in which the character A designates the hollow cap member which is formed of rubber or similar material and fits upon the top of the typewriter key, while B designates the retaining ring which serves to hold the hollow cap member in proper position upon the key. The hollow resilient cap member A is formed with a substantially flat top 1 and annular depending side walls 2 which inclose an air chamber 3. Resting upon the upper surface of the substantially flat top 1 of the hollow cap A is a disk 4 of celluloid or like material upon which the character 5 of the particular key of the typewriter to which the cap is applied is printed. An annular retaining flange 6 which is integral with the hollow cap A and carries an inwardly projecting lip 7 projects upwardly from the periphery of the top 1 so as to engage the edges of the disk 4 and hold the same securely in position, the lip 7 overhanging the said edges of the disk, as indicated more clearly by Figs. 2 and 4. Owing to the fact that the cap member A is formed of some resilient material such as rubber, it will be understood that the retaining flange 7 may be readily stretched and bent outwardly by the fingers a sufficient amount to admit of the letter carrying disk 4 being placed in position or removed therefrom.

The letter carrying disks 4 upon the various hollow cap members A are thus interchangeable and any letter or character can be readily applied to any of the hollow rubber caps. Furthermore, the disks 4 can be made of celluloid or similar material so that the letters or characters printed thereon will not become soiled or worn off by continued use. In this connection it may be mentioned that the letters or characters 5

instead of being printed upon the upper or exposed surface of the celluloid disk 4 are preferably either printed upon the lower face of the celluloid or upon a backing 4^a applied to the lower face of the celluloid disk, so that the printed characters are clearly visible through the celluloid although the actual printing or lettering at no time comes into direct contact with the fingers of the operator. This is a feature of great importance, since a very serious objection to most of the cushion caps of this character is that they are made with the letter vulcanized into the rubber or printed thereon, so that the letters frequently pick off, always become soiled when used to any extent, and being upon a thin layer of rubber do not wear very long. These objections are overcome by the present construction in which the letter or character is carried by the celluloid disk and protected thereby so that it can neither soil nor pick off, and the hollow cushion cap A is formed with thick walls so that it will be very durable and will not wear out with any ordinary amount of use.

The retaining ring B which is employed for holding the hollow rubber cap A in proper position upon the typewriter key C, may be formed of metal and is shown as provided at the upper edge thereof with an inturned flange 8 which fits within an annular groove 9 formed in the side walls 2 of the cap A at a point toward the lower end of the cap. This annular groove 9 has a width somewhat greater than the width of the inturned flange 8 so that the said flange will not interfere in any manner with the compression of the cushion cap when it is struck by the fingers of the operator. The sides 10 of the retaining ring B may be flared downwardly as shown and the said ring may have a polygonal formation, such as is clearly indicated by Figs. 1 and 3. The lower end of the retaining ring B projects below the bottom of the hollow cap A so as to fit around and receive the head of the typewriter key C. Any suitable means may be employed for producing an interlocking connection between the retaining ring B and the head of the typewriter key, and in the present instance the lower edge of the retaining ring B is shown as having an indented or reentrant portion 11 at one side thereof. This extends under the head of the typewriter key at one side thereof, as indicated by Fig. 4, so as to hold the cushion cap against accidental displacement, although by tilting the cushion cap at an angle to the head of the typewriter key it will be obvious that the retaining ring B can be easily removed therefrom or applied thereto. The lower edge or bottom of the hollow rubber cap A may be formed with an inwardly offset and downwardly pro-

jecting annular flange 12 which clears the rim 13 at the top of the typewriter key and rests upon the flat central surface 14 of the typewriter key so as to seal the air chamber 3 and confine the air therein so that it cooperates with the resiliency of the rubber to increase the shock absorbing properties of the device. The exterior diameter of the hollow rubber cap A is substantially the same as the diameter of the head of the typewriter key, and the flange 12 is merely offset inwardly a sufficient amount to clear the rim 13 of the key.

A slight modification is shown by Fig. 5, in which the hollow rubber cap A is identical in construction with that shown by the remaining figures of the drawings and heretofore described in detail. The retaining ring B, however, has a slightly different construction, being comparatively narrow and formed with a series of downwardly projecting prongs 15 adapted to have the extremities thereof bent under the head of the typewriter key, as indicated at 15^a. The upper end of the retaining ring B is secured to the hollow rubber cap A by means of a flange 8, exactly as previously described, although the prongs 15 are substituted for the skirted formation of the retaining ring.

When the cushion caps are applied to the typewriter keys, it will be obvious that the natural resiliency of the soft rubber or like material of which the cap A is formed will serve as a cushion to absorb any sudden shocks due to striking the key with the fingers. This cushioning quality of the cap will be increased by reason of the fact that the cap is hollow and the walls thereof will be distorted to a certain extent when the cap is struck by the fingers, and also by the fact that the air within the interior space 3 is confined in such a manner as to be slightly compressed when the cap is distorted and the top thereof bent downwardly. This cushioning action will not only prevent the finger tips of the operator from becoming sore when manipulating the keyboard of a typewriter, but will also tend to prolong the life of the machine and reduce the wear upon the mechanical parts thereof by eliminating or reducing the sudden shocks upon the parts. Should any one of the hollow rubber caps A become worn so that it may be desired to replace the same, it is not necessary to buy an entirely new set of the cushion caps in order to get a cap having the same particular letter or character printed thereon, since the disk 4 of celluloid can be readily removed from the old rubber cap and applied to a new rubber cap. As previously stated, the characters or letters 5 upon the celluloid disks 4 are protected by the celluloid so that they can not become soiled by use and will not pick off or wear out.

A modification is shown by Fig. 6 in which a different means is utilized for securing the letter carrying disk 4 to the top of the cap. As shown by this Fig. 6 the letter carrying disk 4 is engaged by the in-turned upper edge of a retaining ring 16 which extends around the upper edge of the cap A and has an interlocking connection therewith. This interlocking connection 5 may be brought about in any suitable manner, although in the present instance the lower edge of the retaining ring 16 is shown as bent inwardly so as to engage an annular groove 17 in the side of the cap A. This 10 modified construction of the cap is designed to be applied to the key of a typewriter or other similar machine in the same manner as the forms of the invention previously illustrated and will operate in an identical 15 manner to absorb the shocks and jars so as to reduce the wear upon the machine and prevent the fingers of the operator from becoming sore.

Having thus described the invention, 20 what I claim as new and desire to secure by Letters Patent, is:—

1. A cushion cap for the keys of typewriters and like machines, including a hollow cap formed of elastic material and having an open base and a closed top, the said cap being of substantially the same size and shape as the typewriter key and having a flat top surrounded by an integral disk retaining flange, an interchangeable letter 25 carrying disk fitted removably against the flat top of the cap and held in position by the elastic retaining flange, and means for fastening the base of the cap to the typewriter key.

2. A cushion cap for the keys of typewriters and like machines, including a hol-

low cap of elastic material formed with an open bottom and a closed top, the cap being of substantially the same size as the key to which it is to be applied and having an annular groove in the sides thereof, while the open end thereof terminates in an inwardly offset annular flange adapted to engage the flat top of the key within the confines of the rim thereof, and a retaining ring 45 adapted to fit over and engage the key, the upper end of the retaining ring being formed with an inturned flange received within the before mentioned groove in the side of the cap.

3. A cushion cap for the keys of typewriters and like machines, including a hollow cap formed of elastic material and having an open bottom and a closed top, the upper surface of the top being substantially 50 flat and surrounded by an integral disk retaining flange, and the sides of the cap being formed with an annular groove, while the open lower end of the cap terminates in an inwardly offset annular flange adapted 55 to engage the flat top of a key within the confines of the rim thereof, a letter carrying disk fitted removably against the flat top of the cap and adjustably held in position thereon by the before mentioned elastic flange, and a retaining ring adapted to fit 60 over and engage the key, the upper end of the retaining ring being provided with an inturned flange which is received within the annular groove in the side of the cap. 70

In testimony whereof I affix my signature in presence of two witnesses.

ELLIS H. GEMMILL.
